UNITED STATES PATENT OFFICE.

ARCHIE C. JEFFERSON, OF ST. PAUL, MINNESOTA.

RECIPROCATING CONVEYER.

1,148,688.

Specification of Letters Patent. Patented Aug. 3, 1915.

Application filed April 22, 1914. Serial No. 833,651.

To all whom it may concern:

Be it known that I, ARCHIE C. JEFFERSON, a citizen of the United States, residing at St. Paul, in the county of Ramsey and State 5 of Minnesota, have invented new and useful Improvements in Reciprocating Conveyers, of which the following is a specification.

My invention relates to improvements in 10 reciprocating conveyers.

Its object is to provide a simple and efficient conveyer adapted to coöperate with and be actuated by an ordinary endless carrier, or the like, whereby objects may be 15 transferred, one by one, from a source of supply and placed on said carrier.

A further object is to provide a device of 20 this kind automatically adjustable to accommodate itself to objects of different dimensions.

In the drawings, Figure 1 is a side elevation of my improved conveyer, portions thereof being broken away to show the lugs on one side of the support, and Fig. 2 is a 25 plan view of said conveyer.

Referring to the accompanying drawings, I have illustrated one section 10 of the common horizontal endless carrier, which is supplied with ordinary block-engaging 30 fingers 11 and also with the actuating dog 12, more fully hereinafter described. An inclined block-supporting slide 13 and yielding block-retaining plungers 14, which may be of ordinary or suitable construction, are 35 also shown.

My improved conveyer consists of a pair of supporting brackets 15, the chair 16 slideable thereon and mechanism for reciprocating the chair. Said chair passes backward 40 and forward between the slide 13 and endless carrier (one section 10 thereof being shown) to supply the latter with blocks from the former.

The brackets 15 are fixed in parallel relation on the frame 17 and each of said brackets is formed with a track 18 on its upper edge, a longitudinal slot 19 therein and adjacent lugs 20 and 21 near one end thereof and on the inner side beneath said 50 slot.

The chair 16 comprises a seat 22, supporting webs 23 depending from said seat and a back 24, said seat and back having portions thereof cut away to reduce the weight of 55 said chair. The webs 23 are mounted upon a transverse shaft 25 slideable at its ends

in the slots 19 in the brackets 15, and each of said webs 23 is supplied at its lower end and upon its outer face with a roller 26 adapted to engage the lugs 20 and 21 on the adjacent bracket. The relation of said lugs and rollers is such that when the chair 16 reaches a position near the end of its backward stroke, the rollers 26 engage the lugs 21 and tilt said chair rearwardly and when 60 the chair is moved forward from the rear of the brackets, the rollers 26 engage the lugs 20 and erect said chair. The seat 22 slides upon the tracks 18 when the chair is at the forward ends of the brackets 15 and said seat extends upon either side of the shaft 25 to steady and prevent the tilting of 65 the chair in such position.

The following mechanism is employed to 70 reciprocate the chair. Two toothed quadrants 27 and 28, having arms 29 and 30 with rollers 31 thereon, are pivoted upon the frame 17. These quadrants mesh at opposite sides with the double faced rack bar 32, which is mounted upon the reciprocating 75 shaft 33 slideable within the bearing 34 on said frame. The extensible connecting rod 35 joins the reciprocating shaft 33 with the chair 16. This connecting rod consists of the sleeve 36 pivotally attached to the transverse shaft 25 on the chair and the bar 37 pivotally attached to said reciprocating shaft 33, said bar being slideable within the sleeve and yieldingly retained therein by the spring 38 which is coiled about said 80 sleeve and attached at one end thereto and at its other end to said bar.

The dog 12, above referred to, is fixed upon the carrier 10 in position to engage the 85 rollers 31 on the arms 29 and 30 of the quadrants 27 and 28. The fingers 11 are mounted in rows near the top and bottom of each carrier section 10 and said fingers yield to receive a block from the chair 16 and firmly clamp said block upon the carrier section. 90

In operation the chair, when titled, depresses the yielding block retaining plungers 14 and receives a block 39. Movement of the carrier section 10 from the position and in the direction indicated in Fig. 2 95 causes the engagement of the dog 12 with the roller 31 on the first arm 29 and advances the chair 16. Upon the initial movement of said chair, the rollers 26 engage the lugs 20 and tilt the chair forward until it reaches 100 a vertical position, when said rollers become disengaged from the lugs 20. Near the end 110

of the throw of the arm 29 the block 39 is forced between the yielding fingers 11 and pressed against the carrier 10, said fingers 11 serving to firmly grip and secure the block 5 upon said carrier.

The extensible connecting rod 35 permits still farther movement of said arm 29 so that it may be released from the dog 12. This continued movement of the arm 29 after the 10 engagement of a block with said carrier 10, is permitted, owing to the resiliency of the spring 38, and it will be noted that when the blocks being transferred to the carrier 10 are of varying dimensions they cause the 15 chair to stop in different positions and the arm 29, to be released from the dog 12, has only to swing a greater or less distance against the action of said spring 38. It is therefore obvious that the forward stroke of the chair is automatically varied or adjusted 20 to accommodate blocks of different thickness without interfering with the operation of connected working parts. The second arm 30 is moved by said dog 12 and the 25 chair 16 is returned to the rear of the brackets. Near the end of the backward stroke of the chair the rollers 26 engage the lugs 21 and said chair is again tilted to operate the yielding plungers 14 and receive 30 another block, from the slide 13.

Having described my invention, what I claim as new and desire to protect by Letters Patent, is:

1. In a conveyer, the combination with a 35 carrier and block-feeding device of a stationary support, a chair for blocks, resting on said support and having a slidable, pivotal connection therewith, means operated by the carrier for reciprocating the chair 40 between said feeding device and carrier, and means for tilting the chair toward said feeding device at one end of its stroke to receive a block, said reciprocating means being adapted to yield in moving said chair 45 toward the carrier, whereby a block thereon is yieldingly pressed against said carrier.

2. In a conveyer, the combination with a carrier and block-feeding device of a stationary support, a chair for blocks, resting 50 on said support and having a slidable, pivotal connection therewith, means for reciprocating the chair between said feeding device and carrier, means for tilting the chair toward said feeding device at one end of 55 its stroke to receive a block, said recipro-

cating means being adapted to yield in moving said chair toward the carrier, and temporarily hold a block thereon in resilient contact with said carrier, and means to prevent the tilting of the chair except at said 60 end of its stroke.

3. In a conveyer, the combination with a moving carrier and yielding retaining devices, of a support, a chair movable upon said support, means actuated by the movement of said carrier to reciprocate the chair between the carrier and retaining devices and means on said support for tilting the chair to displace said retaining devices. 65

4. In a conveyer, a pair of brackets, each 70 having a track upon its upper edge and being also formed with a longitudinal slot therein, a reciprocating chair slidably and tiltably mounted in said slots, the seat of said chair being adapted to rest upon said tracks during a portion of its stroke to retain said chair in upright position and means for tilting said chair near the end of one of its strokes. 75

5. In a conveyer, a pair of brackets, each 80 of said branches having a track upon the forward portion of its upper edge and being also formed with longitudinal slots therein, a shaft slidable and tilttable in said slots, a chair fixed on the shaft and adapted to slidably engage said tracks at points on either side of said shaft, a roller on the chair beneath the shaft and lugs adapted to engage said roller to tilt the chair rearwardly and also to replace said chair in upright position. 85

6. In a conveyer, a frame, a support upon the frame, a chair movable upon said support, a pair of toothed quadrants on said frame, an operating arm for each quadrant, 95 a reciprocating rack in mesh with both of said quadrants and a connecting rod between said rack and chair comprising a sleeve pivoted on said shaft, a bar pivotally connected with the rack and slidable within 100 said sleeve and a spring between said bar and sleeve for yieldingly holding the former within the latter.

In testimony whereof, I have signed my name to this specification in the presence of 105 two subscribing witnesses.

ARCHIE C. JEFFERSON.
